ABSTRACT: A support card for one or more disposable female undergarments known in the trade as "panties." The card is loaded with the garments while held in stiffened position in a jig which curves the card transversely of spaced laterally extending score lines. The card is folded upon itself after being loaded with a plurality of such garments, and the card is shaped in such a fashion that leg openings of the garment are retained at protuberances from the edges of the card.

SUPPORT CARD FOR DISPOSABLE UNDERGARMENTS

THE PRIOR ART

The known prior art is best exemplified in the following patents, their class and subclass being also noted:

Heyman	Nov. 19, 1929	206/78
Andrews	July 27, 1937	229/71
Bloom	Mar. 24, 1953	206/46
Getaz	Sept. 15, 1959	206/46
Shenker	July 10, 1962	206/46
Rouder	Oct. 9, 1962	206/7
Murray et al.	July 2, 1968	206/65

SUMMARY OF THE INVENTION

The structure according to the present invention provides a simple and useful device for loading and displaying female undergarments in a folded carton having a display window therein.

THE DRAWING

FIG. 1 is a plan view of a support card according to the present invention;

FIG. 2 is a perspective view showing the support card in a holding jig for the stiffening thereof during loading with an undergarment;

FIG. 3 is a perspective view showing a garment loaded on the support card, which is folded to a position for loading into a container; and

FIG. 4 is a perspective view showing the support card with a number of disposable undergarments loaded thereon, and being inserted into a container. The improved support card according to the present invention is referred to by the reference numeral 10 and comprises a first panel element 11 and a second panel 12, these extending from a central panel 15 and foldably connected to central panel 15 along respective fold lines 13 and 14. The ends of fold lines 13 and 14 converge toward each other along converging portions 16 to meet at an apex point 17 at the edges of the blank 10.

The first panel element 11 is essentially triangular in configuration with converging sloping lines 18 extending from the respective spines 17, the two sloping lines 18 meeting along a generally curved line 20.

Second panel element 12 is defined by a panel edge 19 spaced from the score line 14 and parallel thereto opposed curved edges 21 intersecting score line 14 and panel edge 19.

The second panel element 12 is provided with a protuberance 22 at each side thereof, adjacent score line 14 each protuberance 22 being defined by one of the converging score lines 16 at the ends of the score line 14 and by an edge 23 coextensive with the curved line 21 and spaced from such converging score line 16.

The blank 10 thus far described is adapted to be stiffened during loading thereof with an undergarment, and is held for loading in a jig 20A having a pair of closely spaced vertical guides VG extending upward therefrom, guides VG being spaced according to the thickness of the stock of the blank 10. Each has a generally curved cross section defined by a curved baseline 25, and has a one-half oval shape viewed in elevation.

The so-stiffened blank 10 is adapted to be loaded with an undergarment UG having a waist portion WP and a waist portion opening WOPO, and closed in the lower end thereof at a groin portion G flanked by leg openings O. First panel element 11 is receivable through the waist portion WP and is adapted to support garment UG at the groin portion G thereof. In the loading of blank 10 a waist portion WP moves on to the second panel element 12 to be held thereat in flat position. Groin portion G is also held in flat condition on the panel element 11.

The protuberances 22 extending into each side of the second panel element 12 extend through the leg openings and lock waist portion WP to the second panel element 12, and thereby prevent the unintended removal of the garment from the card.

The garments UG are of the disposable type to be disposed of after one wearing, and the blank 10 is adapted to be loaded with a number of such garments. By reason of the provision of the central panel 15, the plurality of garments may be folded as seen in FIG. 3 without bulging at the fold thereof. The first panel element 11 with the garments loaded thereon is folded into a position of overlying relationship with respect to the second panel element 12. After being folded in the manner described, the folded blank 10 with the garments loaded thereon may be inserted into an outer container C for shipment. The precise details of outer container C form no part of the present invention.

We claim:

1. A support card for one or more disposable undergarments such as panties or the like having groin and waist portions, said support card being formed from a cut and scored blank of paperboard or the like and being adapted to be supported during loading in a jig affording stiffening thereof and comprising:
  - a. first and second panel elements foldably connected along at least one fold line;
  - b. said first panel element being receivable through a waist portion of said garment and to support said undergarment at the groin portion thereof;
  - c. said second panel element being receivable in said waist portion and holding the waist portion of said undergarment in flat position;
  - d. a protuberance at each side of said second panel element for engaging leg openings in said undergarment;
  - e. said fold line having each end thereof adjacent one of said protuberances and enabling said undergarment to have the groin portion folded with respect to said waist portion.
2. A support card according to claim 1 characterized by a pair of spaced fold lines whereby a number of garments may be supported on said card and folded.
3. A support card according to claim 2 wherein said spaced fold lines define a center panel element therebetween to facilitate the folding of said undergarments when said first and second panel elements are folded with respect to each other.
4. A support card for one or more disposable undergarments such as panties or the like having groin and waist portions, said support card being formed from a cut and scored blank of paperboard or the like and being adapted to be supported during loading in a jig affording stiffening of said blank and comprising:
  - a. first and second panel elements foldably connected along at least one fold line;
  - b. said first panel element being receivable through a waist portion of said garment and to support said undergarment at the groin portion thereof;
  - c. said second panel element being receivable in said waist portion and holding the waist portion of said undergarment in flat position;
  - d. a protuberance at each side of at least one of said panel elements for engaging leg openings in said undergarment;
  - e. said fold line having each end thereof adjacent one of said protuberances and enabling said undergarment to have the groin portion folded with respect to said waist portion.
5. A support card for one or more undergarments such as panties or the like having groin and waist portions, said support card being formed from a cut and scored blank of paperboard or the like and being adapted to be supported during loading in a jig affording stiffening of said blank and comprising:
  - a. first and second panel elements foldably connected along at least one fold line;
  - b. said first panel element being receivable through a waist portion of said garment and to support said undergarment at the groin portion thereof;
  - c. said second panel element being receivable in said waist portion and holding the waist portion of said undergarment in flat position;
